UNITED STATES PATENT OFFICE.

WILLIAM H. LING, OF GROVELAND, CALIFORNIA.

PROPELLING DEVICE FOR BOATS.

Application filed February 8, 1922. Serial No. 533,918.

To all whom it may concern:

Be it known that I, WILLIAM H. LING, a citizen of the United States, residing at Groveland, in the county of Tuolumne and 5 State of California, have invented new and useful Improvements in Propelling Devices for Boats, of which the following is a specification.

This invention has reference to boat propulsion.

An object of the invention is to produce boat propellers in the nature of foldable blades which are pivotally supported on the bottom of a vessel and which are actuated 15 by means to impart a reciprocatory movement thereto, the blades being so associated with the operating means therefor to cause the same to swing or fold toward each other on the reverse or non-propelling strokes and 20 to open and spread and to be effectively sustained in such open and spread condition in their propelling stroke, the said blades, in their last mentioned position offering a comparatively broad surface for contact with 25 the water whereby the vessel will be propelled at a rapid speed.

The foregoing, and other objects which will appear as the nature of the invention is better understood, may be accomplished by 30 a construction, combination and operative association of parts, such as is disclosed by the drawings which accompany and which form part of this specification.

In the drawings:

35 Figure 1 is a plan view of a sufficient portion of a vessel to illustrate the arrangement thereon of propelling means in accordance with this invention.

40 Figure 2 is a sectional view on the line 2-2 of Figure 1.

Figure 3 is a sectional view on the line 3-3 of Figure 2.

Figure 4 is an enlarged elevation of one of the pairs of propelling blades.

45 Figure 5 is a sectional view on the line 5-5 of Figure 4.

Figure 6 is a sectional view on the line 6-6 of Figure 2.

50 In the illustrated embodiment of my improvement, the vessel 1 is shown with a flat bottom 2, but it will be understood that the improved propelling means may be attached to any ordinary construction of vessels.

55 The propelling shaft is indicated by the numeral 3, and in the showing of the draw-

ings is arranged centrally and longitudinally in the vessel.

At suitable points, adjacent to the stern of the vessel 1 and preferably at or adjacent to the sides of the said vessel there are housings 4 arranged in opposed pairs and connected by plates 5 which may, if desired, serve as seats for the passengers of the vessel. Each of the housings has arranged therein vertically disposed pairs of spaced 65 guide members 6 for a cross head 7. Each cross head 7 is centrally provided with a longitudinal elongated slot or opening 8. In each of the slots 8, and in contact with the walls thereof is a crank 9. The cranks 70 in the opposed housings 4 are secured on shafts 10, the said shafts being journaled in suitable bearings 11 in the outer walls of the housings and being also journaled in suitable bearings 12 provided on the upper ends 75 of castings 13 which are bolted to the deck or bottom 2 of the vessel 1. Each casting 13 has a longitudinal branch provided with vertical extensions 14 having bearings 15, and in the bearing 15 of one of the castings 80 the end of the shaft 3 is journaled. In the remaining bearings there is journaled a shaft 16 which is in longitudinal alignment with the shaft 3 and in reality, provides an extension of the said shaft 3. 85

Each cross shaft 10 has keyed or otherwise secured thereto a beveled gear 17. The shaft 3 has on its end a gear 18 which is in mesh with one of the beveled gears 17. The shaft 16 has on both of its ends 90 beveled gears 19 and 20 respectively, which are in mesh with the beveled gears 17 on the respective cross shafts 10. From the foregoing, it will be apparent that the turning of the main or propelling shaft 3 will 95 impart a rotary movement to each of the cross shafts 10, through the medium of the shaft 16 and the interengaging elements carried by the said shaft 16, the cross shafts and the main or propelling shaft 3, and as 100 a consequence the cranks 9 will be turned to impart a reciprocatory movement in a vertical direction to the cross heads 7.

Secured to each cross head 7 there is a depending piston rod 20. Each of the piston rods passes through a suitable packing box 21 in the bottom 2 of the vessel 1, and the outer end of each of the piston rods 20 has secured thereto, as at 22 a member 23 whose outer end is widened and 110

bifurcated to provide spaced arms 24 and which has a tongue 25 arranged between the arms 24. Between the arms 24 and the tongue 25 there is journaled a shaft 26 provided with rollers 27, and between the arms, below the tongue 26 there are two spaced stub shafts 28 on each of which is journaled a roller 29.

On the bottom 2 of the vessel at the outer end and approximately in a line with the center of each of the housings 4 there is bolted or otherwise secured a depending bracket 30. To each of these brackets 30 there is pivoted, as at 31 an angle lever.

15 The normally vertical arm of each of the levers is, for distinction, indicated by the numeral 32 and the second angle arm by the numeral 33. The arm 33 is T-shaped in cross section and in reality is in the 20 nature of a track, the same being received between the spaced pairs of rollers 27 and 29, as clearly illustrated in Figure 6 of the drawings. Between the arms 32 and 33 there is a brace connection 34. The arm 25 32 may also be in the nature of a T-iron if desired, but the same has the portion thereof extending beyond the brace 34 round in cross section, the same forming a shaft 26 for the knuckles 35 of the pairs of cooperating propeller blades 36. The lower 30 end of the shaft 37 of the angle lever is headed, as at 38.

The vertical arm 32 of each of the angle levers, above the propeller blades 36 has 35 outwardly projecting keys or feathers 39 which are received in keyways in a collar 40, the said collar having its opposed ends provided with laterally projecting segmental extensions 41 respectively. Each 40 collar has loosely connected thereto by means 42 a rod 43, and pivotally secured to each rod there is a link 44 that passes through a stuffing box 45 in the bottom 2 of the vessel 1. Bolted or otherwise secured 45 to the bottom 1, opposite each of the links 44 there is an upstanding bracket 46. Each bracket has pivoted thereto, as at 47 a link 48, and also secured to the pivot or on the opposite side of each of the said 50 brackets there is an arm 49 that is pivoted, as at 50, one to each of the links 44. Loosely secured to the lower end of each of the opposed pairs of links 48 there is a cross rod 51.

55 To the longitudinally opposed cross rods 51 there are loosely connected rods 52. One of the arms 49 is provided with a lever extension 53, and if desired, the lever may be provided with a spring influenced pawl to engage with a suitable rack bar. By 60 operating the lever 53 all of the arms 49 and all of the links 48 will be simultaneously operated, so that a pull, say in an upward direction will be exerted upon the rods 43 which will move the collars 37 upwardly on the vertical arms of the angle

levers to bring the segmental blocks 44, which form the obstructing elements for the propeller blades, above the said propeller blades. An opposite movement of the lever will bring the blocks 41 downwardly and 70 into contacting engagement with either the front or rear faces of the respective pairs of propeller blades. In this manner it will be apparent that the vessel may be propelled either forwardly or rearwardly without reversing the turning of the engine or propelling shaft 3. It will be further apparent that by holding the lever in its first mentioned position that the obstructing or holding blocks 41 will be raised above the 80 propeller blades so that the rocker levers may be operated on the turning of the shaft 3 without the propeller blades acting on the water, which is an especially desirable 85 feature of the construction, inasmuch as such arrangement permits of the idling of the propellers without halting the operation of the propelling shaft.

It is thought that the foregoing description, when taken in connection with the drawings will fully set forth the construction, operation and advantages of the improvement to those skilled in the art to which such inventions relate, but it is thought necessary to state that the nature 95 of the invention is such as to render the same susceptible to changes in size, proportion, material employed and in other details of construction, and therefore it is to be understood that I am entitled to all such 100 changes from the illustrated embodiment herein set forth as fall within the scope of what I claim.

Having described the invention, I claim:—

1. In a boat propelling means, a shaft 105 constantly rotating in one direction, angle members pivoted to the bottom of the boat, a pair of propeller blades hingedly secured to each angle member, means between the shaft and angle members for imparting a reciprocatory movement of the latter from the former, means slidable on the angle members for contacting engagement with either of the opposed faces of the blades for permitting the blades to close together in either 115 of two directions without reversing the shaft or interfering with the reciprocation of the members.

2. In a boat propelling means, a shaft 120 constantly rotating in one direction, angle members pivotally secured to the bottom of a boat, a pair of propeller blades hingedly secured on each member, means between the shaft and members for imparting a reciprocatory movement to the latter, means on the members in contacting engagement with one 125 of the faces of the blades for holding the blades against turning toward each other, said means susceptible for engagement with the opposite faces of the blades, and said 130

means being also susceptible to movement out of engagement with the blades without interfering with the reciprocation of the blades or the turning of the shaft.

- 5 3. In a boat propelling means, a shaft constantly turning in one direction, vertically movable cross heads actuated by the shaft, guides for the cross heads, a piston for each cross head passing through a packing box
10 in the bottom of the vessel, angle levers pivotally supported on the bottom of the vessel opposite each piston rod, pivot means on each piston rod, anti-frictional means on each of said last mentioned means engaging

one of the arms of each of said angle levers, 15 pairs of propeller blades hingedly secured to each angle lever, segmental blocks slidable on each angle lever, means for moving the same whereby to engage either of the opposed faces of the blades to hold the same 20 against swinging toward each other in one direction and for movement above the blades for permitting of the free swinging of the blades toward each other in either direction without interfering with the reciprocation 25 of the angle levers.

In testimony whereof I affix my signature.
WILLIAM H. LING.
